BIRGER LJUNGSTRÖM, OF STOCKHOLM, SWEDEN, ASSIGNOR TO AKTIEBOLAGET
LJUNGSTRÖMS ÅNGTURBIN, OF FINSPONG, SWEDEN.

RADIAL TURBINE.

1,146,183.

Specification of Letters Patent. Patented July 13, 1915.

Application filed December 14, 1914. Serial No. 877,150.

To all whom it may concern:

Be it known that I, BIRGER LJUNGSTRÖM, engineer, a subject of the King of Sweden, and a citizen of Sweden, residing at Regeringsgatan 52, Stockholm, in the Kingdom of Sweden, have invented certain new and useful Improvements in Radial Steam or Gas Turbines, of which the following is a specification.

10 In radial steam or gas turbines with drum-shaped vane-rings, which contain a number of vanes, arranged axially behind each other and attached to intermediate supporting rings, there arise very great difficulties as to 15 the balancing of the vane rings.

The present invention has for its purpose to avoid or diminish these difficulties. This is attained by forming the vane rings in such a way, that they taper in steps, continuously or otherwise from their fastening point in axial direction instead of being cylindrically formed as has hitherto been the case.

In the accompanying drawings: Figure 1 represents a vertical section of the two outermost vane rings of a pair of turbine wheels embodying my invention and the means connecting said rings to said wheels, the proximate portions of the latter being 20 shown partly in section, partly in elevation and broken away; Fig. 2 represents a similar view, omitting the connections, of a slightly modified pair of vane rings which taper continuously and have smooth inclined 25 meeting faces; Fig. 3 represents another modification having the tops of the vanes in each vane ring in the same horizontal plane, but the intervening supporting rings increasing regularly in height so as to 30 constitute a tapering form as a whole for each vane ring; Fig. 4 represents a view similar to Fig. 3, but reversing this relation of supporting rings and vanes, though retaining the tapering structure of each vane ring as 35 a whole; Fig. 5 represents a similar view of another modification having both the vanes and supporting rings increasing regularly in height, the former step by step, the latter continuously; and Fig. 6 represents a 40 similar view of another modification resem-

bling Fig. 1, but having the steps of the inclined meeting faces of the rings made broad enough to include two vanes in each instance.

45 *a, a'* indicate two turbine wheels, rotating in opposite directions and carrying the two vane rings *b, b'* by means of the intermediate parts *c, c'*.

e indicates the vanes and *d* indicates the rings, supporting the vanes. 60

As shown in Fig. 1 of the drawing the vane rings taper in steps from the fastening point. Hereby, of course, the center of gravity of each ring will lie more near the fastening point, which enables a better balancing of the ring. Instead of being formed as shown in said figure, the vane rings can taper continuously as shown in Fig. 2. Only the supporting rings (see Fig. 3) or only the vanes (see Fig. 4) taper in any way, 70 or the supporting rings and vanes taper in different ways as for instance the former in steps and the latter continuously (see Fig. 5). Further the vane rings can be constructed in such a manner, that each step 75 contains two or more vane lengths (see Fig. 6).

In the embodiment shown in Fig. 1 the steps of two vane rings project into each other. 80

Claims.

1. A pair of turbine wheels, in combination with a pair of vane rings respectively carried thereby, vanes carried by said rings and connections between said wheels and rings whereby each ring is supported by one of said wheels and the other ring is supported by the other wheel, the two rings tapering from their points of attachment to said wheels and in reverse direction with 90 regard to each other.

2. A pair of turbine wheels, in combination with a pair of vane rings respectively carried thereby, vanes carried by said rings and connections between said wheels and 95 rings whereby one ring is supported by one of said wheels and the other ring is supported by the other wheel, the two rings tapering in reverse directions in steps from their points of attachment to said wheels 100

and projecting correspondingly into each other.

3. A pair of coöperating vane rings attached to reversely operating wheels and tapering in opposite directions from their points of attachment by reason of the increase of height of each alternate element in each vane ring, said rings being composed

of vanes and intermediate supporting rings arranged alternately.

In testimony whereof I have affixed my signature in presence of two witnesses.

BIRGER LJUNGSTRÖM.
